UNITED STATES PATENT OFFICE.

STERLING E. NORMAN, OF FRANKLIN, MASSACHUSETTS.

LIQUID-DISPENSER.

1,379,357.

Specification of Letters Patent. Patented May 24, 1921.

Application filed November 14, 1919. Serial No. 338,080.

To all whom it may concern:

Be it known that I, STERLING E. NORMAN, a citizen of the United States, residing at Franklin, in the county of Norfolk and

5 State of Massachusetts, have invented certain new and useful Improvements in Liquid-Dispensers, of which the following is a specification.

This invention relates to improvements 10 in liquid dispensers of the gravity feed type.

An important object of this invention is to provide a liquid dispenser of the class described having novel means for automatically supplying air to the interior of the receptacle when the same is in an operative position whereby air may readily displace the contents of the receptacle upon being discharged.

20 A further object of the invention is to provide a liquid dispenser having novel means for normally closing the discharge spout of the same so that the receptacle may be carried from place to place while in an inverted or operative position.

25 A further object of this invention is to provide a liquid dispenser of the class described which is of highly simplified construction, cheap to manufacture and desirable in use.

30 Other objects and advantages of the invention will be apparent during the course of the following description.

In the accompanying drawing, forming a part of this application and in which like 35 numerals are employed to designate like parts throughout the same,

Figure 1 is a central vertical section through a liquid dispenser embodying the invention.

40 Fig. 2 is a horizontal section taken on line 2-2 of Fig. 1.

Fig. 3 is a horizontal section taken in line 3-3 of Fig. 1.

In the drawing wherein for the purpose of 45 illustration is shown a preferred embodiment of this invention, the numeral 5 generally designates a cylindrical receptacle which, in this case, is especially adapted for the reception of a quantity of lubricating oil. The top 6 may be secured to the sides 50 of the receptacle by double seaming 7 and is provided with a filling opening 8 normally closed by a threaded cap 9.

As illustrated in Fig. 1, a spout 10 is ex-

tended through the top 6 at one edge portion 55 of the same and is held in position by a downwardly extending flange 11 formed by bending the adjacent portion of the top inwardly. It will be noted that one side of the spout 10 flatly contacts with the adjacent 60 side of the receptacle so that the spout is rigidly held in position and is prevented from becoming loosened after continued use. The spout 10 is provided outwardly of the cover with a screw valve 12 which has 65 threaded engagement with one side of the same and is adapted to control the discharge of the oil from the receptacle. In the event that a heavy oil is used, the valve may be partly or entirely removed from the bore 70 of the spout, or in the event of a light oil being used, the valve may be extended a considerable distance across the bore of the spout. An outer removable spout section 13 is arranged in longitudinal alinement with 75 the main spout section 10 and has its inner end portion extended outwardly to form an annular shoulder 14. A coupling 15 is arranged about the outer spout section 13 and has threaded engagement with the main 80 spout section 10 for detachably connecting the outer spout section to the receptacle. The outer spout section 13 may be readily renewed in the event of the same becoming damaged by the machinery being lubricated. 85 Also the detachable spout section 13 may be replaced by another section having a larger or a smaller bore as conditions may require.

The inner end portion of the stationary spout section 10 has an opening 16 extending 90 out through one side of the same for the discharge of the lubricant from the receptacle into the spout. As illustrated in Fig. 1, the spout section 10 is provided beyond the opening 16 with a conical valve seat 17 95 adapted to be engaged by the conical head 18 of a plunger 19. The plunger 19 is guided in its longitudinal movement by the inner end portion of the spout section 10 and by a sleeve 20 carried by the bottom 21. 100 The conical head of the plunger 19 is normally retained seated by a coil spring 22 which, as illustrated, is confined between a retaining disk 23 and the inner portion of the sleeve 20. The lower end of the coil spring 22 engages an annular packing 24 which is snugly arranged about the adjacent portion of the plunger and is seated 105

- on the inner end of the sleeve 20 for preventing the leakage of oil through the sleeve 20. The coil spring serves the double function of normally retaining the plunger 19 seated and of retaining the washer 24 in liquid tight engagement with the guide sleeve 20. If desired the washer 24 may be faced with leather so as to provide a good connection between the same and the sleeve.
- 10 The rear end of the plunger is extended exteriorly of the bottom 21 and is provided with an annular shoulder 25 which forms a stop element for an operating rod 26. The operating rod 26 extends lengthwise of the 15 receptacle and has its lower end portion extended inwardly and looped about the plunger as indicated at 26'. The upper portion of the operating rod is slidably extended through a laterally projecting handle 27 which is arranged on the same side of the 20 receptacle as the discharge spout, with the result that when the receptacle is held in a downwardly inclined position the oil will be directed through the discharge spout. The 25 upper end portion of the operating rod 26 is looped as indicated at 28 for providing a manipulating element adapted to receive the index finger of the hand when it is desired to dispense the oil from the receptacle.
- 30 When the device is in an inverted or downwardly inclined position, a quantity of air is admitted to the same through a sleeve or vent 29 extended through the bottom 21 and connected to the same by an outwardly 35 extending annular flange 30. When in an upright position the vent 29 is closed by a disk washer 31 mounted on the inner portion of a lever 32. The rear end portion of the lever is pivoted to a standard 33 and the 40 outer end portion of the lever is provided with a weight 34 which serves to retain the disk washer 31 over the inner end of the vent 29 when the receptacle is in an upright position. When the receptacle is inverted 45 preparatory to discharging the quantity of oil from the same, the weight 34 operates the lever and thereby causes the washer 31 to be removed from the vent 29 with the result that air is admitted into the bottom 50 or what is then the top of the receptacle. The forward portion of the lever 32 is slidably extended through a vertical U-shaped standard or guideway 35 which is secured to the bottom as indicated at 36. The guideway 35 serves to limit the pivotal movement of the lever and also serves to direct the disk washer 31 to the inner end of the sleeve 29 when the receptacle is returned to an upright position. The air supplying device for the receptacle operates entirely 55 automatically and can only be opened when the receptacle is in an inverted or discharging position. Since the lever 32 is limited in its outward pivotal movement the washer 60 31 is immediately reseated upon the return of the receptacle to an upright position.
- When it is desired to dispense a quantity of oil from the receptacle for lubricating purposes, the receptacle is inverted and the loop 28 is engaged by the index finger of the hand so as to unseat the plunger. As stated above, the vent 29 is opened as the receptacle is inverted so as to admit a quantity of air to the receptacle above the contents of the same.
- 75 When the receptacle is returned to an upright position, the vent 29 is automatically closed by the weight 34 which serves to engage the washer 31 with the inner end of the vent.
- 80 It is to be understood that the form of the invention herein shown and described is to be taken as a preferred example of the same and that such minor changes in arrangement and construction of parts may be made as will remain within the spirit of the invention and the scope of what is claimed.
- Having thus described the invention, what is claimed is:
1. A device of the class described including a receptacle having a top, a spout extending through said top and engaged with one side of the receptacle, the inner portion of said spout being provided with a valve seat and an inlet opening beyond said valve seat, a plunger adapted for engaging said valve seat for closing said opening, and an operating device for said plunger.
- 90 2. A device of the class described including a receptacle having a top, a spout extended through said top and engaging one side wall of said receptacle, a valve seat arranged within said spout, said spout being provided with an opening inwardly of said valve seat, a plunger slidably arranged in said spout and having snug contact with the side walls of the same, the forward end of said plunger being provided with a head adapted for engaging said valve seat, means to normally retain the head of said plunger in contact with said valve seat, and a guide for the rear end of said plunger.
- 100 3. A dispensing receptacle having discharge means, an air inlet sleeve secured to said receptacle, a weight-operated lever pivoted within said receptacle and provided with a valve adapted to engage the inner end of said sleeve, and means to limit the pivotal movement of said weight-operated lever.
- 115 4. A dispensing receptacle having an air inlet, a weight-operated lever pivoted within said receptacle and provided with a washer adapted for closing said air inlet, and discharge means for said receptacle.
- 120 5. A device of the class described including a body having an air inlet sleeve, a horizontally pivoted lever arranged within said

body and provided with a weight at one end, a disk washer carried by said lever and adapted for engaging the inner end of said air inlet sleeve, and means to limit the movement of and guide said lever.

6. A dispensing device including a receptacle, an air inlet sleeve in the bottom of

said receptacle, a weight-operated lever horizontally pivoted within said receptacle and provided with a valve adapted for engaging the inner end of said sleeve, and a U-shaped guide receiving said weight-operated lever.

In testimony whereof I affix my signature.
STERLING E. NORMAN. [L. S.]
